J. GOTTLIEB

MEANS FOR SETTING NONBREAKABLE WATCH CRYSTALS

Filed May 5, 1922

INVENTOR
By Joseph Gottlieb
Clement Phelps Marr
ATTORNEY

UNITED STATES PATENT OFFICE.

JOSEPH GOTTLIEB, OF BROOKLYN, NEW YORK.

MEANS FOR SETTING NONBREAKABLE WATCH CRYSTALS.

Application filed May 5, 1922. Serial No. 558,818.

To all whom it may concern:

Be it known that I, JOSEPH GOTTLIEB, a citizen of the United States, and resident of the borough of Brooklyn, county of Kings, State of New York, have invented certain new and useful Improvements in Means for Setting Nonbreakable Watch Crystals, of which the following is the specification.

The use of glass as a watch-crystal or as a means of covering the face of a watch is not entirely satisfactory when the watch is submitted to extraordinary service. This is particularly true of crystals for wrist or military watches, and means have been devised for guarding or protecting the crystal, but such means are not entirely satisfactory for the reason that they cover the face of the watch to a certain extent and make its observation difficult, further they add to the thickness or bulk of the watch.

Non-breakable watch-crystals have been produced. These crystals, so-called, are made of a particularly hard and clear celluloid or similar material. The nature of this material is well understood and it is known that one of the principal objections to its use as a watch crystal is the difficulty in securing it in the bezel of the watch.

Celluloid watch-crystals are made flat or are cut from a sheet of suitable thin and clear celluloid and must therefore be dished or made concavo-convex before they can be secured to the bezel and it has been found difficult and many times impossible to give these non-breakable crystals a satisfactory shape by means of the fingers only.

The device which I am about to describe is a mechanism designed for the purpose of shaping non-breakable crystals and retaining them in the desired shape adjacent to a bezel and then upon the release of the pressure applied in shaping the crystal it will attach itself to the bezel.

The device has then for its principal object that of assisting in placing non-breakable crystals in watch bezels and the construction and operation of the device will be fully set forth as the specification progresses.

The following is what I consider a good means of carrying out my invention and the accompanying drawings should be referred to for a complete understanding of the specification which follows:—

In the drawings:—

55

Fig. 1, shows a machine fully assembled and in position for operation.

Fig. 2, is a plan view of the base.

Fig. 3, is a plan view of the lever or arm.

Fig. 4, is a plan view of the die or crystal retainer.

Fig. 5, is a reversed plan view of the member shown in Fig. 4.

Fig. 6, a sectional view of the member shown in Fig. 4, and

65

Fig. 7, an elevation of the punch or depressing member.

Similar reference numerals indicate like parts in all the figures where they appear.

In Fig. 1, let us consider that 1 indicates the floor, then 2 would indicate a table of a suitable size and elevated a convenient height from the floor. This table 2 may be independently formed, that is, constructed only for the use and accommodation of my device and if so I prefer that its height should be such as to allow an operator to observe the work while seated before the machine.

Secured to the table by means of the screws 3 and 4 or otherwise is a base plate having extending lugs 5 and 6 through which the screws 3 and 4 pass.

The inner or rearmost portion of this base member is an arm 7 having an upward extension 8 at top of which is a suitable trunnion or bearing 9, perforated as shown by the dotted lines 10 in Fig. 2.

Forward of the arm 7 and formed integral therewith is a cupped shape member 11 having an inwardly projecting flange 12 and it will be noted that I produce a large perforation 13 in the flange 12 and that this perforation passes quite through the bottom of the cup 11. A slot 14 is produced in the arm 7 for a purpose that shall appear later. Pivoted to the upwardly extending mem-

85

ber 8 and to the trunnion or bearing there-in is an arm or lever 15 having a plurality of downward extensions 16 perforated to receive the pivot 17 by means of which the arm or lever 15 is connected to the upward extension 8. At the forward end of the lever 15 is a downwardly extending portion 18 having a perforation or recess 19 and a lug 20 formed integral with the underside of the arm 15 receives a pivot 21 to which the operating rod 22 is attached.

90

95

100

105

The rod 22 is made separable and adjustable and the two positions of this rod are secured together by means of screws 23 and 24. The lower section of the rod 22 is 5 pivoted to a foot lever 25 at the outer end of which is a step 26.

The inner end of the foot lever 25 is pivoted at 27 to a floor bracket having parallel arms of different lengths. The arm 28 10 extends above the pivot 27 to a considerable degree and the opposite arm 29 extends upward only sufficient to provide a support for the pivot 27. A foot piece 30 is perforated to receive screws 31 which secure 15 the foot piece and floor bracket to the floor or other convenient support.

The spring 32 secured to the upwardly extending member 28 and also to the lever 25 tends to retain the lever 25 elevated and 20 by so doing also elevates the arm or lever 15 and parts attached thereto.

The member 44 which I call a die and which is shown in detail in Figs. 4, 5 and 6 is received in the cup 11 and rests upon 25 the flange 12. This die member has an interior shoulder 33 and a hollowed portion 36 on the other side and it is to be noted that the diameters of the shoulders 33 and 34 differ. The member which I call a punch, 30 shown in elevation in Fig. 7 has a body 38 and an upward projection 39. The lower face of the body 38 is slightly convex as shown at 40.

I provide a plurality of these so-called 35 punches and dies, but the outer diameter of all of the dies is the same and the diameter of the projection 39 is in each instance the same.

I will now describe the operation of my 40 device using the same reference characters, so that the function of each part may be readily understood.

The levers 15 and 25 being elevated, a die 45 of a suitable size is selected and placed in the cup 11. The underside of the die rests upon the flange 12 and it will be understood that the flange and the adjacent face of the die should be free of obstruction 50 so that the die may rest fairly upon the flange 12.

A punch approximately the diameter of the recess 34 or 36 of the die, though somewhat smaller than the recess, is next selected and its upward projection inserted into 55 the socket of perforation 19. The crystal is next placed upon the shoulder 33 or 35 and the bezel arranged over the crystal and probably supported upon the die exterior to the shoulder just mentioned. Now a 60 pressure of the foot of the operator upon the step 26 will depress the punch and will force the crystal downward into the recess 34 or 36 and the edges of the crystal will then project upward through the bezel.

The bezel is retained in position by the fingers of the operator and when the pressure of the foot is released the crystal will expand into the crystal receiving cut into the bezel, the whole operation taking but an exceedingly short space of time. 65

The position of the bezel during the operation of setting a crystal is shown by the dotted lines B in Fig. 1.

As before mentioned I may provide a plurality of dies, but as all will be of approximately the same construction having two operative faces, it is only necessary to show the one as illustrated. It should, however, be understood that modifications may be made within the scope of the appended 80 claims without departing from the principle or sacrificing the advantages of the invention.

Having carefully and fully described my invention, what I claim and desire to secure by Letters Patent is:—

1. A device for setting non-breakable crystals including a die having recesses of various diameters in opposed faces thereof, shoulders on opposed faces of said die, and a punch adapted to operate into said die, the operating face of said punch being convex. 90

2. A device for setting non-breakable crystals comprising a cup shaped member having an inwardly projecting flange and a die arranged therein, a lever over said cup shaped member and having a recess and a punch arranged therein and means for operating said punch into said die. 95

3. A device for setting non-breakable crystals comprising a cup shaped member, an arm extending therefrom, an upward projection from said arm and having a bearing, a lever pivoted to said bearing and having a recess, a punch in said recess and a means for depressing said punch toward and into said cup shaped member. 100

4. A device for setting non-breakable crystals, comprising a cup shaped member and a die arranged therein, a projection from said member and a bearing formed therein, an arm pivoted in said bearing, a punch in said arm, in combination with means for moving said punch toward said cup shaped member, said means comprising a foot lever and a floor bracket, said floor bracket having an upward extension, to which said lever is pivoted, a spring attached to the upper end of said extension and to said foot lever and an operating rod from said lever to said arm, all combined for joint operation, as and for the purpose set forth. 110

Signed at the city, county and State of New York, this 25 day of April, 1922. 125

JOSEPH GOTTLIEB.
